RECORDING APPARATUS

Ernst S. Svensson, New York, N. Y., assignor to
 The Kron Company, Bridgeport, Conn., a corporation of Connecticut

Application March 4, 1939, Serial No. 259,787

17 Claims. (Cl. 234—5.4)

This invention relates to recording apparatus and particularly to power driven mechanisms of rugged nature suited to severe conditions of service such as the recording of weights measured by heavy industrial scales. This application is a continuation in part of my co-pending application Serial No. 83,870, filed June 6, 1936, which has eventuated in Patent No. 2,198,139.

An important object of the improvements is to construct a recording apparatus for the stated purpose whose operating parts are strong and perform substantial extents of movement thereby to eliminate requirements for extreme accuracy and fine dimensioning of the parts.

A related object is to support and constrain the operating parts at well spaced points to render them individually accessible and to augment the amount of movement cooperatively performed by the parts at their points of operative engagement.

A further object is to separate a portion of the apparatus consisting of those mechanisms which operate the printing type from that portion of the apparatus which comprises the more rugged and heavier power mechanism, and to provide, for transmitting power from the latter mechanism to the former mechanism, a single movable part which by convenient detachment from either mechanism will permit that mechanism to be removed from the apparatus as a unit and replaced by a similar or different unit with ease and dispatch when the apparatus requires servicing in the field.

A related object is to afford a separation of the above mentioned two sets of mechanism which will enable them to be separately housed if desired whereby the printing mechanism may be protected from dirt and lubricants which are commonly present in power mechanisms.

A further object is to provide a cycle stop power mechanism which will automatically terminate a manually initiated cycle of recording movement and to provide a manual controller for initiating the cycle of movement which does not require the operator to wait or attend the controller after it is once manipulated to initiate the recording operation.

A further object is to provide in a power mechanism for recording apparatus suitable safeguards yieldingly to check the coasting movement of the power mechanism after the source of power has been automatically disconnected therefrom and before some predetermined position of the power driven parts has been reached at the end of each recording operation.

A further object is to govern the motivation of the entire apparatus from a single power operated shaft and a plurality of cams rotated in unison thereby.

5 In the drawings:

Fig. 1 is a front view of the entire recording mechanism.

Fig. 2 is a side elevation looking from the left at Fig. 1 and further shows the portions of stepped members which may be employed to determine the value registering positions of the type segments, Fig. 2 being drawn on a smaller scale than Fig. 1.

Fig. 3 is an enlarged fragmentary view taken 15 in section on the plane 3—3 in Fig. 2 looking in the direction of the arrows.

Fig. 4 is a correspondingly enlarged fragmentary view taken in section on the plane 4—4 in Fig. 5 looking in the direction of the arrows.

Fig. 5 is a plan view of the upper portion of the mechanism in Fig. 1 and is drawn on a corresponding scale.

The recording mechanism as a whole may be viewed as comprised of two main systems of parts 25 which may respectively be termed the type registering mechanism, and the power and printing hammer mechanism.

Type registering mechanism

This mechanism is best shown in Figs. 1, 2, 4, and 5. One or more horizontal feeler rods 10 are mounted for longitudinal sliding movement in apertures through the main vertical frame plate 11 and in respectively aligned rectangular apertures through the offset bracket 12 shown mounted on the exterior surface of frame plate 11 in Figs. 2 and 5. Feeler rods 10 are equipped with any suitably thin edged feeler terminals 13 which are constantly urged toward steps on peripherally notched wheels 14, 15, etc., by individual light springs 16, each of which surrounds a rod 10 and is compressed between a collar 17 carried thereby and the frame plate 11. The stepped wheels 14 and 15 are representative of any adjustably positionable stops which may be located respectively in the paths of the different feeler terminals 13. For an example of one possible purpose and function of such stepped wheels reference may be had to the co-pending application of Glenn E. Weist, Serial No. 753,842, now

Patent No. 2,173,746 wherein similar discs are designed to be rotatively positioned in accordance with the weights of a load and by the automatic action of a weighing scale in order that the 55 weights measured thereby may be recorded.

The stepped wheel peripheries preferably act to limit sliding of rods 10 to selected portions of their total permissible travel, which portions of travel accord respectively with the spacing of type characters 18 that project from the peripheral edge of a type segment 19 of which segment four are shown pivotally mounted upon a common shaft 20 in Figs. 1 and 5. Shaft 20 is supported by and spans the space between the left and right sides of an upper frame casting 21 which is shown in Fig. 2 to be mounted at its rear end upon the main vertical frame plate 11, and removably held thereon by bolts 32.

The upper end of each type segment 19 is pivotally connected to a clevis 22 from which a connector 23 extends rearwardly and terminates in a similar clevis 24 pivotally connected to the forward end of a corresponding feeler rod 10. The effective length of any connector 23 may be adjusted finely by a threaded coupling 25 interposed between separate rod parts of the connector and having threaded engagement therewith and lockable in adjusted position by the end nuts 26 which also have threaded engagement with the rod parts.

In Figs. 1 and 5 the type segments 19 are seen to be axially spaced by suitable collars 27 which surround the support shaft 20 and it will be plain that a considerably greater number of type segments than the four shown, together with additional manually settable type segments carrying any desired data, can be accommodated within the space between the sides of the frame casting 21.

The normal, or non-printing position of the type segments is as pictured in full lines in Figs. 1, 2 and 5 and this position is brought about through the action upon all of the rods 10 of an actuating bail comprised of the transversely disposed rod 28 connecting and carried by the upper ends of two vertical bail arms 29 and 30. One segment is indicated by broken lines in Fig. 2 as shifted to a printing position. The bail arm 29 swings at the left of the frame casting 21 and the bail arm 30 swings at the opposite or right side of the frame. Both of these bail arms swing in unison about a lower pivot point as will later be described, and they carry the bail rod 28 in a path of travel corresponding with the travel of depending projections 31 respectively carried by the rods 10 (see Fig. 4). Thus the bail rod 28 may act to force all of the rods 10 simultaneously toward the front against the opposition of their compression springs 16 or by movement toward the rear may release all of rods 10 to the individual action of such springs as individually and respectively limited by the notched wheels 14, 15, etc.

The inking ribbon is designated as 54 in Figs. 1, 2 and 5 of the drawings. Between the ribbon spools 60 and 85, the ribbon extends around a left guide pulley 92 and a right guide pulley 93, each of which pulleys is rotatively mounted by a construction more fully disclosed in my aforesaid co-pending application. The shoulder stud 94 retains and gives bearing to the guide pulley and penetrates the extremity of a horn-like projection 95 of the frame casting. The rearwardly projecting end of stud 94 serves to mount a pressor bracket 96 which is rigidly retained thereon by the fastening nut 97. The pressor bracket 96 is most clearly shown to afford sliding support for the stem 98 of a pressor disc 99 which is constantly urged inwardly by the compression spring 100 so that pressor disc 99 yieldingly bears upon

the inking ribbon 54 while the latter is in contact with its guide pulley 92 or 93.

Power and printing hammer mechanism

This mechanism is located completely below the floor plate 102 which at its rear end is supported upon the bracket 150 and at its forward end is supported upon the upstanding portions of the lower frame casting 151 which in effect form spaced standards. Most of the power and printing hammer mechanism is supported between the two sides of frame casting 151 which itself derives support from the main frame plate 11 to which it is secured at the rear end in removable manner by bolts 33.

Any suitable electric motor 152 may be separately mounted upon the main frame plate 11, and the motor shown has its shaft equipped with a drive worm 153. The worm wheel 154 is in mesh with worm 153 and rotates the shaft 155 to which it is fixed. Shaft 155 has bearing at each of its ends in the frame casting 151 and also carries fixed thereto the pinion 156. Pinion 156 is in mesh with the large gear 157 which is fixedly carried by the cam shaft 158. Cam shaft 158 also spans and has bearings in the two sides of frame casting 151 and fixedly carries between the frame sides a cam 159 for controlling the printing hammer. Outside the left bearing in the frame casting shaft 158 carries a cam 160 for controlling the bail arm 29 and thereby the type registering and ribbon feed mechanisms. At its left extremity in Fig. 1 cam shaft 158 also rotates an electric switch operating cam 161 thereby to automatically interrupt the circuit to the electric motor 152 when a cycle of recording action has been completed.

The printing hammer comprises a strip of suitable platen material 162 securely mounted on the top surface of a hammer block 163 which at both ends is guided for vertical sliding movement in the frame casting 151 by means of grooves or ways sunk in the latter. Block 163 carries the horizontal rod 164 which pivotally supports two depending links 165 and 166. The lower ends of these links are pivotally engaged by a similar horizontal rod 167 which is swingingly supported by and connects the free ends of two forwardly projecting arms 168 and 169 which arms are fixedly mounted upon shaft 170 in spaced relation. The ends of shaft 170 have bearings in the frame casting 151. At a central portion, shaft 170 fixedly carries the hub 171 of the cam follower arm 172 whose rearwardly extending end is equipped with a roller 173 riding in contact with the periphery of cam 159. At the right side of the frame casting, shaft 170 fixedly carries the stub arm 174 with which is connected the hammer actuating spring 175 whose rear end is anchored to a bracket 176 mounted on the main frame plate 11.

The outer left surface of the frame casting 151 is equipped with two bearing lugs 177 and 178 which guide a longitudinally sliding plunger device consisting of a rod 179 rigidly carrying the clevis 180 at its rear end and thereby pivotally connected to the lower extremity of the bail arm 29. Both this bail arm and the corresponding bail arm 30 at the right side of the frame casting are rigidly mounted on the opposite extremities respectively of a pivot shaft 181 which extends through and has bearings in both sides of the frame casting.

The rod 179 of the plunger device may have a sufficiently loose fit in the bearing lug 177 to permit the pivot pin 182 in clevis 180 to follow the arc of swing of the lower extremity of bail

arm 29 but rod 179 is made rigid with a sliding bar 183 at its forward end which is preferably of rectangular cross section and a good sliding fit within a corresponding aperture through the bearing lug 178. A roller 184 is pivotally carried at the forked extremity of bar 183 and is constantly pressed against the periphery of cam 160 by the compression spring 185 loosely surrounding rod 179 and bearing against the lug 177 at its rear end while its forward end bears against a thrust washer 186, fast to bar 183.

187 represents a current supply wire running directly to the windings of the electric motor 152. Another supply wire 188 electrically connects one switch contact 189 to the source of current supply. The other switch contact 190 is connected to the motor by a wire 191 so that making and breaking electrical contact between parts 189 and 190 will respectively start and stop the motor. A conductive switch plug 192 is adapted to electrically bridge contacts 189 and 190 when moved to the left in Fig. 2 and is carried in insulated relation at the rear extremity of a horizontal bar 193 which has sliding bearing in a stationary bracket 194 and is limited in its movement toward the front by the engagement with said bracket of a cross pin 195. The forward end of bar 193 is slidingly supported in a downwardly and laterally extending portion of the frame casting 151 and is equipped with a manual operating handle 196. A dog 197 is pivoted at 198 to the bar 193 and straddles this bar in a bifurcated lower portion 199 as shown in Fig. 3 and projects upwardly for engagement by the cam 161.

Dog 197 is constantly urged counter clockwise in Fig. 2 by springs 200 and 201, being normally disposed in upstanding position as shown in Fig. 2 by the engagement of the rear edge of its bifurcation with the top edge of bar 193 whereas the higher disposition of its front bifurcated edge permits at times relative swinging of the top of dog 197 toward the right in Fig. 2 by overpowering of the tension in springs 200 and 201. This tension, however, is sufficiently strong to enable counter clockwise rotation of cam 161 in Fig. 2 to pick up and impel the bar 193 to its position shown in Fig. 2 by engagement with dog 197 for the purpose of opening the switch.

Operation of type registering and printing mechanism

The power operated type registering and printing mechanism is shown in Figs. 1 and 2 as its parts are positioned when the electric motor 152 has been cut out of circuit automatically at the end of a cycle of recording action. During a single cycle of such action, the cam shaft 158 performs a half turn counterclockwise in Fig. 2. The cycle is initiated by manually pushing the switch knob 196 as far as it will go toward the left in Fig. 2. In this movement the dog 197 will tip toward the right as permitted by the yielding of spring 200 and will slip under the lower end of cam 161 (at that time stationary) and spring erect into its perpendicular relation to bar 193 after it has passed the end of cam 161. The switch plug 192 then completes the circuit between the switch contacts 189 and 190 causing motor 152 to start running thus rotating worm 153, worm wheel 154, shaft 155, pinion 156, gear 157, and thereby the cam shaft 158 together with the three cams 159, 160 and 161

fixed thereto, in a counterclockwise direction in Fig. 2.

A very small amount of rotation of cam 160 will permit roller 184 which rides in contact therewith, to move suddenly toward the right under the power of the spring 185 and the consequent pulling of the lower end of bail arm 29 toward the right about its pivot 181 will throw the upper portions of bail arms 29 and 30 toward the left in unison together with their carried bail rod 28. By thus moving away from the projections 31 on all of the feeler rods 10 simultaneously, each of these rods is released or delivered to the thrust of its individual spring 16 which will carry each feeler terminal 13 toward the left in Fig. 2 until it is intercepted or blocked in its movement.

While many devices are known in the art of registering mechanisms for blocking the spring urged advance movement of type positioning feeler elements for conditioning the type to print some recordable value, any of which devices may be used for that purpose with my improved recording mechanism, there is herein illustrated for that purpose the differently notched peripheries of respectively separate wheels such as 14 and 15 of which there may be one for each different feeler terminal 13 and which may be rotatively positioned by the automatic action of a weighing scale (not shown), or otherwise.

As each of rods 10 moves toward the left in Fig. 2 a distance determined by the notched wheels 14 and 15, it will, through its connection to a corresponding type segment 19, swing that segment counterclockwise in Figs. 2 and 9 a corresponding degree of travel about the pivot shaft 20 so that the proper one of type characters 18 will be positioned in printing position vertically beneath the segment pivot. Fig. 2 represents one of the type segments 19 by broken lines as having been swung to a suitable printing position.

When the proper positioning of all type segments 19 has been thus accomplished, cam 159 will have rotated far enough in Fig. 2 to discharge the roller 173 from its highest peripheral point into the segmental notch in cam 159 whereupon under the power in spring 175, the follower arm 172 will abruptly swing downwardly in Fig. 2 causing counterclockwise rotation of shaft 170 and by means of arms 168 and 169 causing the connecting rod pivots 167 to be abruptly elevated. By this action the hammer block 163 is caused to deliver a smart blow upwardly through the action of the connecting links 165 and 166 so that the platen 162 momentarily presses upwardly against the type characters which are in its path on all of the segments 19, a rectangular aperture 103 in the floor plate 102 accommodating this action.

Thus by means of the inked ribbon 54 which is stretched laterally slightly above the floor plate 102 in alignment with the platen 162, a record will be printed from all of the type segments 19 which have been moved to printing position, upon any piece of paper or cardboard which may be interposed between the ribbon and the top surface of the floor plate 102.

The cam shaft 158 continues to travel after the record has been struck and in so doing proceeds to restore both the bail arm 29 and hammer block 163 to their starting positions shown in Fig. 2 whereby all of the type segments 19 and feeler rods 10 are correspondingly restored. When the follower rollers 173 and 184 have thus

arrived at the diametrically opposite high points on the peripheries of their respective cams, the top end of cam 161 will have rotated to a position before completing its half turn in which it will engage and force to the right the top end of dog 197 in Fig. 2. Springs 200 and 201 are sufficiently strong to pull the switch block 192 out from between contacts 189 and 190 without permitting the dog 197 to swing upon its pivot 198 so that all of the parts become restored to their positions in Fig. 2 except that the three cams 159, 160, and 161 are diametrically reversed. These cams, however, are symmetrical with respect to any diameter through their axis so that a subsequently repeated half turn of cam shaft 158 will precisely repeat the cycle of recording operation which has been described. After current has been cut off from motor 152, there may be slight variation in the amount of overrun of the parts which are rotated thereby due to inertia, but a check on this inertia effect will be exerted by dog 197 after bar 183 has been positively stopped by the pin 185 engaging bracket 194 owing to the tension in spring 200.

For additional assurance against too much overrun travel of cam shaft 158 after the motor is de-energized, the bump 149 may be formed on the periphery of cam 159, which, upon engaging with roller 173 will augment the yielding resistance to continued rotation of the cam shaft 158 before the cam 160 shall have coasted far enough counter-clockwise to recede from the path of roller 184. If springs 200 and 201 are made sufficiently weak they will stretch before overcoming the frictional cling of contacts 189 and 190 upon the switch block 192 but will finally overcome this cling and thereby produce a snap action of block 192 to the right to cause a quick breaking of the circuit as is desirable when it is important to minimize arcing.

For brevity in the appended claims, the two bail arms 29 and 30 and their connecting structure are termed an impeller or movement transmitter it being clear that all power for motivating the parts of the type registering and ribbon feeding mechanism is transmitted therethrough and requires only to be disconnected from the parts 28 and 40 to operatively dis-associate the lower power mechanism from the upper type positioning mechanism. In fact, only disengagement of rack bars 40 and 41 from their guide pins 44 and 50 is necessary to permit removal and replacement of the type registering mechanism as a unit without disconnecting the bail 29, 30 from any of its associated parts.

The advantages of these improvements may be obtained by the use of parts differing widely from the exact shape and arrangements herein disclosed to illustrate the invention, and the following claims will be understood to include by their terms all fair equivalents for the particular parts and constructions to which they refer.

I claim:

1. In recording apparatus including recording characters, the combination of, a source of power, a device constructed and arranged to perform an excursion for making a record from said characters, a shaft rotatable by said source of power, means to transmit motion from said shaft to said characters, two double-lobed cams on said shaft, connections actuated by one of said cams to cause said record making device to perform its said excursion at least twice during a single revolution of said shaft, means to deprive said shaft of the power by which it is rotated before each of said

excursions is repeated including a power disconnecting member, and connections operably relating said member to the second of said cams in a manner to cause said member to disconnect the source of power from said shaft at least twice during said single revolution of the latter.

2. In recording apparatus the combination defined in claim 1 in which each of the said cams is symmetrically shaped with respect to any diametrical line passing through its axis of rotation and in which the said cams are held in constant rotative relation such that a half turn of both cams completes the said excursion of the said record making device and also operates the said power disconnecting member to deprive the said shaft of power.

3. In recording apparatus an electrically powered recording mechanism including a cam having a working face contour which repeats itself around the periphery of the cam adapted to be intermittently rotated substantially less than a full turn by alternate application and cut off of power, a record striking device constructed and arranged to be motivated by less than a half revolution of said cam in a manner to complete a cycle of recording action during said half revolution, a second cam, a source of power adapted manually to be energized independently of the movement of said second cam, and connections operated by said second cam in a manner automatically to deenergize said source of power a plurality of times during one complete turn of said second cam.

4. In recording apparatus, electrically powered mechanism as defined in claim 3 together with a spring biased stop member disposed in the path of travel of the said cam in a manner yieldingly to oppose coasting thereof after its said deceleration begins.

5. In sectionally constructed recording apparatus, the combination of, frame work including a standard carrying a vertically elongated guideway and determining the location of a printing station at the top thereof, a power mechanism comprising a section of said apparatus extending rearward from the bottom of said standard, an impression striker guided by said standard to perform vertical movement toward and away from said printing station, a type positioning mechanism superimposed above and extending rearward from the top of said standard and presenting type at said printing station for cooperation with said striker thereat to print a record, and means to transmit movement from said power mechanism to said type positioning mechanism including a lever paralleling and longer than said standard swingably mounted on said framework near the rear of said mechanisms and constructed and arranged operatively to connect said mechanisms.

6. In a sectionally constructed recording apparatus, the combination defined in claim 5, in which the said frame work is sectional, and comprises a vertically elongated holding structure, a horizontally elongated lower frame bracket detachably mounted on said holding structure and carrying the said power mechanism, and a horizontally elongated upper frame bracket detachably mounted on said holding structure and carrying the said type positioning mechanism, the said transmitting lever being detachably related to each of said mechanisms whereby either of said mechanisms may be removed from the recording apparatus as a unit without disturbing the other of said mechanisms.

7. In a sectionally constructed recording appa-

ratus as defined in claim 5, the combination defined in said claim in which the said type positioning mechanism includes pivotally mounted type carrying segments, together with a series of separate springs connected to bias the said type carrying segments respectively away from non-printing position, and an impelling element motivated by the said means to transmit movement in a manner to overcome the bias of said springs and thereby force said segments into non-printing position.

8. In sectionally constructed recording apparatus, the combination defined in claim 5 in which the said impression striker includes a horizontally elongated platen block, together with vertically extending guideways stationed on the said standard beneath the said printing station and slidably engaged by the ends of said platen block in a manner to guide the latter in a vertical path of movement, and devices operatively connecting the said power mechanism to said platen block.

9. In recording apparatus, the combination of, an apparatus support frame, a type carrying segment pivotally mounted on said frame for swinging movement, a rectilinear guideway on said frame, a stop sensing feeler element constrained by said guideway to slide in a straight path of lengthwise travel, a floating rod-like coupling pivotally connected at one end to said feeler and at the opposite end to said segment, a spring operating between said frame and said feeler element in a manner to urge the latter in a direction away from said segment, and means to impel said feeler element in a direction toward said segment against the bias of said spring.

10. In recording apparatus, an electro mechanical system adapted both to complete and to terminate a manually initiated cycle of recording action effected by substantially less than a full turn of a motivating cam, including in combination with a plural lobed motivating cam, recording mechanism, a follower engaging said cam connected to repeatedly actuate a portion of said recording mechanism during a single full revolution of said cam, a manually shiftable electric switch control member, an electric motor electrically connected to be energized and de-energized by movements of said member in respectively reverse directions, and means rotated in unison with said cam constructed and arranged to shift said member in a direction to repeatedly deenergize said motor during a single revolution of said cam and means.

11. In recording apparatus, the combination defined in claim 9 in which said floating coupling includes means constructed and arranged to vary the length of said device and simultaneously to maintain the rigidity thereof.

12. In recording apparatus in combination with printing mechanism, a power driven cam, a follower for said cam connected to operate said printing mechanism, means to deprive said cam of driving power, and a spring biasing said follower in relation to said cam in a manner to oppose movement of the former by the latter, said cam having a portion of its follower contacting surface shaped and arranged to move said follower an extraordinary distance against the bias of said spring thereby to increase the force with which said spring opposes coasting travel of said cam after the latter is deprived of its driving power.

13. In recording apparatus the combination defined in claim 17, in which the said motor control means includes electrical switch contacts for

stopping and starting said motor, a contact operating member mounted and arranged to be movable free from bias between motor starting and motor stopping position, a spring biased latch dog carried by said member, the said second one of said cams being connected to be rotated by said motor and shaped and positioned to engage said dog in a manner to impel said contact operating member in a direction opposite to that in which said dog is biased.

14. In recording apparatus the combination with shiftable recording characters of, an electric motor, a device constructed and arranged to perform an excursion for making a record from said characters, a shaft rotatable by said motor, means to transmit motion from said shaft to said characters, plural actuating cams rotated in unison by said shaft, connections actuated by one of said cams for causing said excursion of the record making device, electrical motor control means including a member operably related to a second one of said cams constructed and arranged when moved thereby to de-energize said motor before said excursion is repeated, together with a handle device constructed and arranged to move said member reversely and independently of the last said cam thereby to re-energize said motor, the said motor control means including an electric switch for energizing and de-energizing said motor, a switch actuating bar supported for lengthwise movement, a dog pivoted to said bar, a spring biasing said dog to a definite position relative to said bar so that said dog projects therefrom into the path of movement of said second one of said cams, and a handle carried by said bar, the said dog being constructed and arranged to yield against the resistance of said spring in a manner to permit manual shifting of said bar in a direction to actuate said switch independently of the position of said cam.

15. In recording apparatus the combination with shiftable recording characters of, an electric motor, a device constructed and arranged to perform an excursion for making a record from said characters, a shaft rotatable by said motor, means to transmit motion from said shaft to said characters, plural actuating cams rotated in unison by said shaft, connections actuated by one of said cams for causing said excursion of the record making device, electrical motor control means including a member operably related to a second one of said cams constructed and arranged when moved thereby to de-energize said motor before said excursion is repeated, together with a handle device constructed and arranged to move said member reversely and independently of the last said cam thereby to re-energize said motor, the said motor control means including, electrical switch contacts for stopping and starting said motor, a contact operating member mounted and arranged to be movable free from bias between motor starting and motor stopping position, a spring biased bifurcated element pivotally connected to said contact operating member in its bifurcated portion and further shaped and arranged to straddle said member in a manner to abut thereagainst at the crotch of said bifurcated portion thereby to limit the extent of swinging movement of said element relative to said member, said second one of said cams being connected to be rotated by said motor and shaped and positioned to engage said element in a manner to impel said contact operating member in a direction opposite to that in which said element is biased.

16. In recording apparatus the combination, with shiftable recording characters, of an electric motor, a device constructed and arranged to perform an excursion for making a record from said characters, a shaft rotatable by said motor, plural actuating cams rotated in unison by said shaft, means to transmit motion from said shaft to said characters including one of said cams, connections actuated by one of said cams for causing said excursion of the record making device, electrical motor control means including a switch operating member operably related to one of said cams constructed and arranged to be moved thereby in a switch-opening direction to de-energize said motor before said excursion is repeated, together with devices constructed and arranged to move said member in a direction different from said switch-opening direction to enable said member to escape said cam and thereby free said member for switch closing movement to 20

17. In recording apparatus the combination with shiftable recording characters of, an electric motor, a device constructed and arranged to perform an excursion for making a record from said characters, a shaft rotatable by said motor, means to transmit motion from said shaft to said characters, plural actuating cams rotated in unison by said shaft, connections actuated by one of said cams for causing said excursion of the record making device, electrical motor control means including a member operably related to a second one of said cams constructed and arranged when moved in one direction thereby to de-energize said motor before said excursion is repeated, together with a handle device constructed and arranged to move said member in a reverse direction and independently of the last said cam, thereby to re-energize said motor.

ERNST S. SVENSSON.

CERTIFICATE OF CORRECTION.

Patent No. 2,332,819.

October 26, 1943.

ERNST S. SVENSSON.

It is hereby certified that error appears in the printed specification of the above numbered patent requiring correction as follows: Page 4, second column, line 37, claim 4, before the word "said" insert --first--; and that the said Letters Patent should be read with this correction therein that the same may conform to the record of the case in the Patent Office.

Signed and sealed this 21st day of December, A. D. 1943.

Henry Van Arsdale,

Acting Commissioner of Patents.

(Seal)
